(No Model.)

W. H. ROACH.
ROCKING ATTACHMENT FOR CHAIRS.

No. 471,080.

Patented Mar. 15, 1892.

Fig. 1.

UNITED STATES PATENT OFFICE.

WILLIAM H. ROACH, OF HIGH POINT, NORTH CAROLINA.

ROCKING ATTACHMENT FOR CHAIRS.

SPECIFICATION forming part of Letters Patent No. 471,080, dated March 15, 1892.

Application filed April 11, 1891. Serial No. 388,556. (No model.)

To all whom it may concern:

Be it known that I, WILLIAM H. ROACH, a citizen of the United States, residing at High Point, in the county of Guilford and State of North Carolina, have invented certain new and useful Improvements in Rocking Attachments for Chairs; and I do hereby declare the following to be a full, clear, and exact description of the invention, reference being had to the accompanying drawings, which form part of this specification.

This invention has relation to platform rocking-chairs, and has for its object the provision of a platform rocking attachment adapted to be applied to chairs of ordinary construction, so as to immediately transform such chairs into platform rocking-chairs.

My invention consists in the novel construction, combination, and arrangement of parts hereinafter described and claimed.

In carrying my invention into effect I provide two similar base-boards, such as are commonly employed to form the base-pieces of an ordinary platform-rocker, and to these base-boards I attach, by properly-arranged levers and braces, tilting or rocking arms, which are provided with sockets adapted to receive the legs of a chair, the whole being so arranged, as will be hereinafter specifically described, that by placing the legs of a chair in the sockets on the rocking arms, the chair will be immediately capable of use as a platform-rocker.

Referring to the accompanying drawings, Figure 1 is a side elevation of a chair with my improvement applied thereto; Fig. 2, a top view of one of the rocking attachments, and Fig. 3 a front elevation of the chair.

A A designates two similar sections of wood, which constitute the bases of the rocking attachment.

B designates a rocking arm, which is pivotally supported at a short distance above and parallel with the base A upon braces a a, which are secured to said rocking arm by a bolt or pivot b. The braces a a incline from opposite directions toward the pivot b, and are suitably secured to the base A.

The rocking arm B is slotted at C C, and

in these slots are placed metallic rings or loops D D, each of which has a screw-threaded tongue e, that projects through the slot, and is provided with a nut E, by means of which the rings may be drawn farther into the slots to tighten the grasp upon the legs F F of the chair G. The legs F F of the chair G fit into the rings D D, and project a considerable distance through the same, so far that the height of the chair when the rocking attachment is applied is not much greater than the chair without the attachment.

In addition to being pivotally supported upon the braces a a the rocking arm B is attached to the base A by means of two sets of toggle-levers h h i i at each end. The toggle-levers h h are pivotally attached to the rocking arm B by means of bolts h' h', and the toggle-levers i i are pivotally secured to the bases A A by bolts i' i', and the levers h h and i i are pivotally secured together by bolts k k.

If desired, the bases A A may be connected together by suitable cross-braces, and the rocking arms B B may be similarly connected, so that the rocking attachment will form a connected structure; but for rendering the attachment easy to pack and transport, I would suggest that such cross-braces, if employed, be so arranged as to be easily detachable. The attachment, as described, can be very readily manufactured at a low price, and when attached to a chair of ordinary construction will serve to transform such chair into a platform-rocker.

If it is found that the chair rocks too easily on the base, the fault may be corrected by tightening up the bolts that secure the toggle-levers together and to the base and rocking arm.

Having described my invention, I claim—

1. A rocking attachment adapted to be attached to a chair and comprising a base, a rocking arm pivotally attached to standards projecting upwardly from said base, and means, substantially as described, for detachably securing the legs of a chair to said rocking arm, as set forth.

2. In a rocking attachment for chairs, the

combination of bases A A, rocking arms B B, braces *a a*, to which said rocking arms are pivotally secured, and provided with rings D 5 for the reception of the legs of a chair with the pivoted levers *h* and *i*, whereby the movement of the rocking arm is limited, substantially as described.

In testimony that I claim the foregoing I have hereunto set my hand this 17th day of March, 1891.

WILLIAM H. ROACH.
